(57) **CLAIM**

The ornamental design for a medical device handle for a surgical tool, as shown and described.

DESCRIPTION

FIG. 1 is a front view of the claimed design;

FIG. 2 is a rear elevation view of the claimed design;

FIG. 3 is a left elevation view of the claimed design;

FIG. 4 is a right elevation view of the claimed design;

FIG. 5 is a top plan view of the claimed design;

FIG. 6 is a bottom plan view of the claimed design; and,

FIG. 7 is a perspective view of the claimed design.
